BOOKBINDING METHOD AND MEANS

Robert Alonzo Williams, Chicago, Ill.

Application March 8, 1943, Serial No. 478,326

13 Claims. (Cl. 281—28)

The principal object of this invention is the provision of a bookbinding method and means for securing sheets, pages or leaves together in loose-leaf fashion, that is to say in an assemblage in which the several leaves or pages are not secured to each other at the binding margin, but are each freely strung on the binding means, as distinguished from the closed type of binding in which the leaves are sewn, glued, or stapled together along the binding edge.

More specifically, it is an object to provide a binding means which may be made from inexpensive and readily procurable materials, such as paper, sized cloth, and like materials of relatively flexible quality adapted to take an adhesive or agglutinant employed in the binding.

A further object is the provision of a binding in the form of an elongated strip having a plurality of binding fingers projecting laterally therefrom at intervals along the length of the strip, the fingers being adapted to pass through slots in the leaves to be bound and then turned back for engagement between lips or flanges forming part of said strip.

A further object is the preparation of the binding strip in laminated form from superimposed elongated strips of paper or the like, which have been glued together throughout their length excepting along one longitudinal edge, the unglued or unattached edge portions providing the separable lips or flanges aforesaid, and the binding fingers or prongs being stamped or otherwise cut from the remainder of the prepared strip.

Another object is the provision of a method of preparing the binding strips in which two rolls of glued tape are unwound with their respective glued surfaces facing each other, the two strips being passed between rollers or the like, so arranged that the two strips will be caused to adhere to each other at the mid-portions thereof, but not along their opposite longitudinal edge portions, whereby separable lips or flanges are provided along said longitudinal edge portions, the glued strips being cut in appropriate lengths, and thereafter being subjected to a stamping operation in which the binding fingers or prongs are formed, said stamping operation being effected in a manner to provide two complete binding strips from each severed length of tape.

Other objects relate to the provision of a binding consisting of an elongated strip portion with lateral binding fingers adhered to the strip portion after being passed through the matter to be bound; to the provision of opposite flange or lip portions on the strip portion for securing the

ends of the binding fingers; to the method and means for preparing binding strips with a minimum wastage of strip stock; and to the various features of novelty and utility which will appear hereinafter as the following description proceeds in view of the annexed drawings in which:

Fig. 1 is a perspective view of the strip-forming means which employs a heat-fusing adhesive on the strip stock;

Fig. 2 is a perspective view of a prepared strip which has been stamped or die-cut to form two bindings;

Fig. 3 is a perspective view of the stamped strip of Fig. 2 after the two bindings have been separated, following the stamping or die-cutting operation;

Fig. 4 is a perspective fragment of a book with the binding inserted preparatory to the forming-up operation;

Fig. 5 is a perspective fragment of a book with the binding formed-up or completed;

Fig. 6 is a perspective view of a modified strip-forming means adapted to the employment of glued strips or stock.

Referring to Fig. 1, the novel binding is prepared by a process which employs two rolls 20 and 21 of paper or cloth tape which ranges from one and one-half to two inches in width, depending upon the length of binding finger or prong desired.

The underside of the top roll 20 is coated with a heat-fusible adhesive 22a of known type commonly available on the open market, while the upper side of the lower roll 21 is coated with a layer 22b of the same kind of adhesive (the adhesive on both strips being indicated by the motting thereon).

The free ends of each strip are fed in superimposed relation, with their adhesive surfaces 40 engaged, between forming rollers 23 and 24 so as to be pressed firmly together. One of the forming rollers, preferably the lower one, 24, has a hollow shaft 24a into which is fitted an electric heating rod or coil 25, adapted to heat the lower roller 24, which is of metal.

As the superimposed strips are pulled through the forming rollers (by means not shown), the lower heated roller 24 causes the adhesive on both strips to fuse, and the resulting coherence 50 secures the two paper or cloth strips together in the manner illustrated by the formed portion of the strip issuing to the right of the rollers, at 26.

An important feature of the process resides in 55 the provision of beveled edges 23a and 23b at

each end of the upper roller 23, which results in leaving the opposite longitudinal edge portions 27 and 28 of the formed strip unattached, so that a pair of divergent lips or flanges 27a and 27b, on one side, and 28a and 28b on the other side, are provided along the opposite edges of the strip.

It is important in the method of preparing these binding blanks or strips, that the web or stock strip 20 or 40, which is to be biased or curled, shall be fed between the rollers 23 24, or 45, 46, at an angle A (see Figs. 1 and 6) of approximately 30° to 40° to the plane of movement of the other tape.

Considering the lower strip 21 or 41 to move in the horizontal plane shown in Figs. 1 or 6, it may be stated for purposes of description that said plane contains a tangent which is common to both rollers in the plane of movement of the composite strip between the rollers, and therefore the strip portion which is to be curled should be fed at an angle A away from this tangent and in a direction away from the other strip.

Any kind of adhesive or gluing substance may be used in the process with either paper or cloth or similar fibrous stock; and the strips may be pre-coated, or the adhesive or agglutinant may be applied just prior to feeding the strip stock into the pressing members or rollers.

In order to apply the curl or bias which results in the edgewise flanges or lips, the beveled roller, at least, should be about as wide as the strip or web stock, as shown in Fig. 1; and the width of the beveled surface or curling formation should be about the width of the desired flange or lip portion.

The formed strip 26 is next cut off at a desired length and placed in a stamping or die-cutting machine (not shown), and a series of alternate prongs or fingers is cut through so that two complete bindings 27x and 28x are formed (see Fig. 3), each binding having its own set of spaced, laterally-extending binding prongs or fingers 27xy and 28xy, respectively. These individual bindings are now ready for use.

As illustrated in Fig. 4, a stack of leaves to be bound, 29, has prepared therein a series of binding slots 30 extending along the binding margin thereof, each slot being of a width to receive a corresponding one of the fingers 28xy, for example; whereupon the binding strip 27x has its several fingers inserted in the slots 30, preparatory to the forming-up operation and insertion of the fingers between the lips or bifurcations 28a, 28b.

In a modified form of binding, illustrated in Fig. 6, the adhesive coatings 42a and 42b are of the water-soluble kind, such as ordinary animal glue, and the underside of the top strip passes over a moistening means, such as the brush 43, rotating in a water pan 44, so that the adhesive coating 42a, at least, is moistened, and thereafter caused to adhere to the lower strip in passing beneath the pressure rollers 45 and 46. Roller 45 has opposite end portions beveled as at 45a, 45b, as in the method of Fig. 1, but the heating means 24a of Fig. 1 is omitted in Fig. 6.

In other respects, the composite or formed strip portion 47 issuing from between the presser rollers, is identical to the strip portion 26 of Fig. 1, opposite divergent or open flange or lip portions 48a, 48b, on one side, and 49a, 49b on the other side, being formed as in the first method of Fig. 1. Moreover, the glued strip portions, after being cut to desired length, are stamped or die-cut, as

in Fig. 2, to provide two complete binding strips or blanks of the type shown in Fig. 3.

It may be noted that in both methods of forming the novel binding (Figs. 1 and 6) the flanges 21a, 21b, or 49a, 49b, respectively, tend to remain spread apart, owing to a curling effect or bias imparted by the combined effects of adhesion and bias produced by the bevel means 23b or 45b, as the case may be.

10 Numerous advantages attach to the novel binding means, and important economies in material result from the method of forming the bindings. The paper or cloth stock used in preparing the binding strips is of non-critical nature and may be easily obtained; the mechanism necessary for the preparation of the binding strips is simple and easily manipulated, and the resulting binding is adequately strong for mostly all binding purposes, the cloth binding being exceptionally satisfactory in this respect, and nearly as cheap as the paper type.

By forming or cutting two individual binding pieces from a single formed strip in the manner illustrated in Figs. 2 and 3, wastage is reduced to a minimum. The bindings are light in weight and may be shipped in large quantities at little expense, taking up little room in stock quantities. Also, the material of which the bindings are fabricated lends itself to the receipt of an imprint of identifying data, which is frequently important in bookbinding to keep jobs separated. Moreover, the bindings are so light and flexible that they conform themselves very readily to the shape of the backbone of the bound sheaf and assist in permitting the bound leaves to turn easily and lie open.

While paper, cloth, particularly sized cloth familiar in the bookbinding arts, and analogous materials like cardboard, are suggested as suitable materials for the novel binding, the use of other materials of equivalent qualities adapted to the various operations of the binding process, are all contemplated by this disclosure, the invention is not intended to be limited to the precise details set forth herein for the purposes of illustration and description, excepting only as may be expressly provided in the appended claims.

Having thus described my invention, discovery, and improvement, what I claim and desire to protect by Letters Patent of the United States is:

1. A binding of the class described comprising a relatively elongated strip of laminated flexible material having laminae separated to form opposite flange portions along one edge, and a plurality of integral laterally extending binding fingers projecting from an opposite edge and each looped back with a free end portion engaged between said flange portions, the matter to be bound being strung on the looped portions of said fingers.

2. A binding of the class described comprising a relatively elongated strip formed of superimposed, adhesively joined strips with a longitudinal side portion at which said strips are not joined but left separated to form opposite lips, said elongated strip having a plurality of laterally projecting binding fingers on an opposite longitudinal side portion, said fingers being adapted to pass through material to be bound and each having a free end portion secured between said lips so as to form binding rings, engaged with said matter to be bound.

3. A binding comprising a composite strip formed of superimposed layers of fibrous material secured together, said strip having an edge por-

tion with a plurality of integral binding fingers arranged therealong, each finger having a free end adapted to be passed through material to be bound, said strip having a second edge portion at which said layers are not secured together as aforesaid, said free ends of the fingers being adapted to be received between said unsecured layer portions for adhesively securing the finger ends therebetween with said fingers in looped condition to provide binding rings.

4. A binding comprising an elongated composite strip of fibrous material, said strip being composed of superimposed strip portions adhesively joined throughout their extent excepting along one longitudinal edge portion, said unjoined edge portions forming opposite lips, said composite strip having integral, lateral binding projections arranged along an edge portion opposite said lips, each said projection having a free end, said free ends being fixedly secured between said lips, whereby said binding projections form looped stringers adapted to hold leaves thereon in loose-leaf style.

5. The method of forming a binding of the class described which comprises feeding adhesively coated individual strips of flexible material between pressing members to form a composite strip, with said individual strip portions joined in median parts but not along longitudinal edge portions of the composite strip, whereby to leave opposite, separable flanges along at least one edge of said composite strip, thereafter cutting said median parts through to form a plurality of binding fingers extending laterally of said flanges and each provided with a free end adapted to be received between said flanges by looping said fingers.

6. The method of making a binding of the class described, which comprises passing strips between pressing members, one or more of said strips having an adhesive coating on a surface opposite another of said strips, said strips being adhesively joined into a composite strip by pressing action of said members, one of said pressing members being provided with a bias-forming means, one of said strips, at least, having a longitudinal edge portion biased away from the corresponding edge portion of the confronting strip, whereby to form unjoined, opposite flange portions along the edge of said composite strip.

7. The method of forming a composite binding strip which comprises feeding at least two strips of flexible tape between pressing rollers, at least one of said tapes having an adhesive coating confronting the opposite tape, said adhesive coating being of a type which is rendered actively adhesive by application of heat thereto, heating one of said rollers, at least, one of said rollers having a beveled end portion confronting an edge portion of one of said tapes and adapted to curl said edge portion, last-mentioned, away from the other tape, whereby longitudinal edge portions of said composite strip are left unattached so as to provide opposite lips along an edge of said strip.

8. The method of preparing a composite binding tape which comprises feeding a pair of tapes between pressing rollers, at least one of said tapes having a glue coating on a side thereof confronting the other tape, moistening said coating prior to passage of the tapes between said rollers, curl-

ing one longitudinal edge of one tape, at least, away from the other tape by feeding the tape to be curled between said rollers at an angle to a common tangent of said rollers and away from the other tape, the roller which is disposed on the side of displacement of the tape to be curled having a curling formation opposite the edge to be curled, whereby opposite longitudinal flanges are left along at least one edge of said composite tape.

9. A method for preparing a composite binding tape which comprises adhesively joining a pair of superimposed elongated flexible tapes by feeding them into juxtaposition with cementitious material therebetween, biasing a longitudinal edge portion of at least one tape out of the plane of the latter during said feeding and joining operation so as to leave said edge portion and the confronting edge portions of the companion tape unjoined, whereby to provide a pair of opposite, separable lip flanges along one edge, at least, of said composite tape.

10. The method of claim 9 further characterized in that both longitudinal edge portions of at least one of said tapes are biased as aforesaid to provide the said pairs of lip flanges along both opposite longitudinal edges of the composite tape, and stamping interfitting, laterally extending fingers in sections of the median portions of the composite tape so that alternate fingers remain attached, at one end thereof, respectively, to corresponding portions of the composite tape, each said last-mentioned tape portion including, respectively, one of said pairs of flange lips, whereby to procure two bindings from each said section of the composite tape.

11. In an apparatus for forming composite binding tape, cooperable presser rollers of predetermined width adapted to press strip material, of approximately the same predetermined width, together by passage of the material between the rollers, at least one of said rollers having a beveled portion adjoining an end thereof beneath which a particular edge portion of one of said tapes, at least, passes, said last-mentioned tape being fed at an angle to a tangent common to said rollers in the direction of movement of said material therebetween, whereby said beveled portion biases said particular edge portion away from the corresponding edge portion of the other tape, such that said last-mentioned edge portions remain in separated relation in passing between said rollers.

12. Binding of the loose-leaf variety comprising a stringer of elongated form adapted to be passed through the matter to be bound, said stringer being laminated with laminae separated at one end to form a pair of confronting lips, and the opposite end of said stringer being cementitiously secured between said lips after being passed through said matter to be bound, whereby to form a closed ring-like binding.

13. In a binding of the class described, binding means including a finger portion comprising superimposed layers of flexible material cementitiously joined with unjoined portions forming opposite lips, said finger portion being adapted to pass through matter to be bound, and having an extremity cementitiously secured between said lips to form a binding loop.
